UNITED STATES PATENT OFFICE

2,058,003

COLON IRRIGATOR

Holden H. Davies, Pasadena, Calif.

Application April 11, 1935, Serial No. 15,766

1 Claim. (Cl. 128—229)

My invention relates to a colon irrigator and has for its object to provide an irrigator which is adapted to be removably disposed between the bowl and the seat of a water closet, without any 5 fastening means whatsoever. Means are also provided to supply water at a predetermined temperature and pressure to the nozzle of the irrigator preferably using the water from the hot and cold water faucets of a lavatory and 10 interposing a pressure regulating mixing valve in the conduit leading to the nozzle.

With the above and other objects in view which will appear as the description proceeds, my invention consists in the construction and arrangement of parts hereinafter described and claimed.

In the accompanying drawing which forms a part of this specification I have illustrated a preferred embodiment of my invention, and in which

Fig. 1 is an elevation with parts in vertical 20 cross section.

Fig. 2 is a partial plan view of the nozzle and its support, showing its disposition on the rear portion of a closet bowl.

Fig. 3 is a side view of Fig. 2 with portions 25 broken away for clearness of illustration.

Fig. 4 is an elevation partly in section of the mixing and pressure regulating valve.

Fig. 5 is a sectional view on line 5—5 of Fig. 4.

Referring to the drawing, W indicates a water 30 closet bowl of any preferred construction, provided with the customary seat S pivoted to the top rear as is common. The colon irrigator comprises an elongated nozzle 10 provided with a perforated head 11. I prefer to use a nozzle construction in which the stem is rather small in 35 diameter so that the nozzle will not interfere with the flushing out of the colon when the nozzle is in use. The nozzle is rigidly mounted by means of an elbow 12 to a pipe 13 extending 40 at an angle rearwardly therefrom. The pipe 13 is connected by means of a T 14 to a horizontal pipe 15 closed at one end 16. The pipe 15 is mounted for rotation in a horizontal bearing 17 formed at one end of a metal plate 18.

45 As shown in the drawing, the shape of the plate 18 is a trapezoid and is adapted to lie flat on the top rearward portion of the bowl W and against the pivot posts P to which the seat S is hinged. The plate 18 has a cutaway portion 18' to accommodate the T 14 and the arm 13 when the latter is partially rotated.

At the end opposite from 16 the pipe 15 is provided with a handle portion 19 extending forwardly at an angle whereby the pipe 15 with the 50 arm 13 and the nozzle may be partially rotated

as hereinafter described. Water at a predetermined temperature and pressure is supplied to the arm 19 of the pipe 15 and 13 in the nozzle 10 as follows: Flexible tubes 20 and 21 are respectively connected to cold and hot water faucets C and H and lead respectively to inlet nipples 22 and 23 of a mixing and pressure regulating valve shown as a unity at 24. The same consists of a base 25 from which extends the tubular portion 26 having a mixing chamber 27 5 communicating at its lower end with a valve chamber 28 at its top. The valve chamber is of a larger diameter than the mixing chamber 27 and is provided at its lower end with a conical valve seat 29 against which is seated a valve 30. 10 The same is square in horizontal cross section and is provided at its lower end with a conical portion 31 to seat on the valve seat 29 and close the mixing chamber. A helical spring 32 interposed between a removable cap 33 and the valve 30 keeps the latter on its seat. The cap 33 is provided with an outlet port 35.

An outlet nipple 36 leads from the mixing chamber 27 and communicates by means of a flexible tube 37 provided with a shutoff valve 38 to 25 branch arm 19 of the pipe 15.

Operation

The shutoff valve 38 is closed so that when 30 opening the hot and cold water faucets, hot and cold water enters through the inlet nipples 22 and 23, the mixing chamber 27 of the mixing and pressure regulating valve 24, the pressure of the water will unseat the valve 30 allowing the water to pass out through outlet port 35. It will be understood that the pressure regulator is so constructed as to permit water of comparatively low pressure only to pass to the nozzle 10. By inserting a thermometer in the outlet port 35 or ordinarily by feeling the temperature of the water 40 issuing therefrom with the hand, the hot and cold water faucets are regulated until the desired temperature is obtained; then the shutoff valve 38 is opened permitting now the water of the desired pressure and temperature to flow to nozzle 10. The person using the irrigator sits on the seat and by manipulating the arm 19 will swing the nozzle 10 upwardly for positioning and use. It should be noted here that the plate 18 which constitutes the support of the nozzle 10 is 45 loosely mounted on the rear portion of the bowl, thereby allowing a slight sliding adjustment laterally and forwardly so that the nozzle can be easily positioned.

Various changes in the construction and ar- 50

angement of parts may be made by those skilled in the art without departing from the spirit of my invention as claimed.

I claim:

- 5 A colon irrigator comprising a plate adapted to be loosely mounted between a water closet bowl and its seat and provided with a bearing along its forward edge, a pipe mounted horizontally in said bearing for partial rotation, said pipe
10 having an angular offset portion extending from

the bowl and constituting an arm for partially rotating the pipe, a rigid conduit fast to said pipe and extending toward the center of the bowl and provided with an upwardly extending nozzle, a flexible tube connected to the angular offset portion, and means to supply water at a predetermined temperature and pressure to said flexible tube.
